UNITED STATES PATENT OFFICE.

CHARLES S. ERLANGER, OF ELBERON, NEW JERSEY, ASSIGNOR TO THE B. V. D. COMPANY, OF NEW YORK, N. Y., A CORPORATION OF DELAWARE.

UNDERWEAR.

1,402,406.

Specification of Letters Patent. Patented Jan. 3, 1922.

Application filed June 9, 1921. Serial No. 476,119.

To all whom it may concern:

Be it known that I, CHARLES S. ERLANGER, a citizen of the United States, and resident of Elberon, county of Monmouth, 5 and State of New Jersey, have invented certain new and useful Improvements in Underwear, of which the following is a specification.

My invention relates to undergarments 10 and has for its object a construction of such garments such that, although made almost wholly of an inelastic woven fabric, it will nevertheless possess that degree of elasticity and flexibility which is requisite for comfort and the varying strains of use. Other 15 more specific objects of the invention will appear from the description hereinafter and the features of novelty will be pointed out in the appended claims.

20 In the accompanying drawings which illustrate an example of the invention without defining its limits, Figure 1 is a rear view of the improved undergarment; Fig. 2 is a face view of the insert thereof, and Fig. 25 3 is a diagrammatic view illustrating certain features of the invention.

The undergarment in the drawings represents a union suit and comprises the customary body 5, legs 6 and arm openings 7 30 and further includes the usual fastening devices (not shown) whereby the garment is closed down the front and any convenient and suitable crotch construction and rear flap and closure, the garment being generally constructed of relatively inelastic (woven) fabric.

The use of garments of this general character, known as athletic undergarments has, during the last twenty-five years, become 40 almost universal and many efforts have been made during that period of time to produce such garments in a manner that will adapt them most conveniently and at low cost to the varying strains of use. When the garment is constructed entirely of inelastic fabric all strains will ultimately manifest themselves in opening seams or rents in the fabric itself. It was consequently realized long ago that for an enduring garment of this 45 type the interposition of an elastic or knit

fabric portion was essential. It is apparent that such an elastic insertion, when of restricted width, will have its edges, transverse to its elasticity, sewed to the corresponding edges of the inelastic fabric, so that no 55 stretch would be possible at those points but only, and to a very limited degree, at the intermediate points, and whatever occurred the strain would always be placed upon the attaching stitches as well as the weakly 60 intermeshed threads of the elastic section where attached. It has consequently been customary to use a relatively narrow elastic waist band of considerable length capable of taking care of the various strains which 65 are effective between the upper and lower inelastic parts of a union suit.

In studying these types of garments for a great many years I have concluded that the inelastic top and bottom sections of the 70 garment can be safely permitted to take up a great many of the ordinary strains provided there is incorporated in the garment, in a certain special way, an elastic element which, for a certain set of possible strains, 75 will co-operate with the inelastic parts of the garment in such manner that all of the strains, instead of being taken up by the elastic fabric itself, are partially taken up by the strength of the inelastic fabric, supplemented only, when necessary, by the 80 elastic element. The construction devised by me, as shown in the drawings, involves the use of an elastic member 8 which, by reason of its general shape and position with respect to the inelastic parts of the garment, 85 brings about certain advantages hereinabove generally referred to.

The insert 8 comprises a section of relatively elastic, preferably knit fabric or other 90 material constructed in a form in which it is of greater width at an intermediate point in a direction transverse to its elasticity than at its opposite ends. In other words, those opposite edges of said insert which extend in the direction in which it is elastic converge inwardly from intermediate points toward the opposite ends of said insert. With the described arrangement, as strains 95 are applied to the insert in the direction of 100

its elasticity tending to stretch it in substantially its surface planes, said insert contracts in width at its intermediate point of greater width or, in other words, the opposite edges referred to straighten out so that an increased stretch or degree of flexibility is provided in said insert without disturbing its elasticity. The described result may be obtained in a variety of different ways as, 10 for instance, by constructing the insert of pentagonal form in which the side edges 9 incline inwardly in opposite directions from the intermediate points 10. The precise outline may be varied so long as the characteristics are preserved.

The insert is preferably located at the back of the garment in the region of the waist-line and is set into the relatively inelastic fabric of the body 5 and secured in 20 place by sewing 11.

Thus, as the garment is subjected to strains when worn in directions indicated, for instance, by the various arrows in Fig. 3, the insert 8 will be stretched in approximately 25 the plane in which it is located and in doing so will cause the intermediate portions of the side edges 9 to adjust themselves in directions parallel with the waist line; that is to say, the opposite points 10 in the illustrated example will move toward each other 30 and thus will provide a much greater degree of elasticity and give, in the garment, at the waist-line than if the side edges 9 were defined by straight lines which extend at right angles or approximately so to an imaginary line extending about the waist of the garment. As the insert is contracted at its intermediate points because of stretching in the direction of its elasticity, the fabric of 40 the body 5 will naturally be drawn into conformity. With an insert of given size the garment is thus of maximum elasticity and comfort without requiring any complicated or extensive insertions of relatively elastic bands and the like. The arrangement of the present insert is such that the increased stretch and degree of flexibility is secured without disturbing the elasticity of the insert, which always returns to its normal position when relieved of strain. This is due 45 to the fact that the increased stretch is not produced so much by actual stretching of the weave of the fabric as it is by manipulating it mechanically as it were; that is to say, the component parts of the edges 9 act 50 in the nature of toggles or levers pivoted together at the points 10, which move inwardly under the stretch and thus permit said edges 9 to elongate or straighten out. 55 Various positions assumed by the insert under strains are diagrammatically illustrated by the various dotted lines in Fig. 3, it being understood that these are simply examples of the operation of the invention. In 60 this diagram the dotted lines *a* indicate the

effect of an upward pull at the apex of the insert; the dotted lines *b* indicate the effect of a downward pull at the base of the insert; *c* indicates the effect of a pull in opposite directions, and *d* the effect, approximately, 70 of a pull in an angular direction.

The insert is easily applied to the garment, a particularly convenient manner of incorporating the insertion in a union suit being illustrated in Fig. 1. As there shown, the back fabric piece 14 is united to the side pieces 12 by an angularly disposed seam 13 running from the arm openings 7 toward the center of the waistline. This seam 13 also serves as the attaching means for one edge of the insertion 8. This construction has the advantage of simplicity in the parts used and of economy in uniting the parts and avoidance of lateral angles cut in a single piece of fabric such as might cause ripping or weakness at the hinge of the toggle lever action.

It is not my intention to claim the use of an angularly outlined elastic insertion as such in an undergarment, since such insertions can readily be incorporated therein, without employing my invention, at points where they only encounter special local strains, as where the knees or elbows, in flexing, tend to press against the fabric insertion located at those spots. Such insertions, so located and so functioning, play no role in the strains affecting the garment as a whole and I therefore have no concern with them and lay no claim thereto.

Various changes in the specific form shown and described may be made within the scope of the claims without departing from the spirit of my invention.

I claim:

1. The combination of a union suit of relatively inelastic fabric and an insert of elastic woven material combined with said relatively inelastic fabric at the back of the garment and having its opposite peripheral portions extending along lines which gradually approach each other from intermediate points, said intermediate points of the peripheral portion being arranged to move inwardly under a strain to provide an increased stretch in said insert in said plane without disturbing its elasticity.

2. The combination of a union suit of relatively inelastic fabric and an insert of elastic woven material combined with said relatively inelastic fabric at the back of the garment in the waist line region thereof, said insert being of pentagonal form, the corners formed by the side edges being arranged to move inwardly in approximately the plane of said insert under a strain, to provide an increased stretch in said insert without disturbing its elasticity.

3. An undergarment of the union suit type comprising an upper body portion consisting

of side pieces of relatively inelastic fabric, a back piece of relatively inelastic fabric united to said side pieces by angularly disposed seams extending from the arm openings toward the longitudinal center line of the garment and terminating at the waist line thereof, and an insertion of relatively elastic fabric attached to the back piece and secured to the side pieces by said angularly disposed seams. ¹⁰

In testimony whereof I have hereunto set my hand.

CHARLES S. ERLANGER.
